UNITED STATES PATENT OFFICE.

THOMAS BENFIELD, OF NEWARK, NEW JERSEY.

DESIGN FOR A WATCH-CASE.

SPECIFICATION forming part of Design No. 21,483, dated April 19, 1892.

Application filed March 17, 1892. Serial No. 425,366. Term of patent 7 years.

To all whom it may concern:

Be it known that I, THOMAS BENFIELD, a subject of Her Majesty the Queen of Great Britain, residing at Newark, in the county of Essex and State of New Jersey, have invented and produced a new and original Design for Watch-Cases, of which the following is a specification, reference being had to the accompanying drawings, forming part thereof.

Figure 1 is a plan view of my new and original design for a watch-case. Fig. 2 is a sectional view thereof, taken on the line X X on Fig. 1.

The leading or essential feature of the design consists of a series of ribs A, convex in cross-section and in the form of loops, such ribs or loops A being disposed or arranged as shown in Fig. 1, the intervening space or surface containing the ribs B, also convex in cross-

section, as shown in Fig. 2 of the drawings, 20 and curved in their length, as shown in Fig. 1. The center of the case is left plain, as shown at C. The several portions may, it is manifest, be engraved, chased, or otherwise ornamented as desired. 25

It is apparent that this design is equally well adapted for the ornamentation of lockets and other similar articles.

Having described my invention, what I claim as new, and desire to secure by Letters 30 Patent, is—

The design for a watch-case, as herein shown and described.

THOMAS BENFIELD.
